UNITED STATES PATENT OFFICE.

WILLIAM J. C. KENYON AND WINFIELD S. KING, OF OMAHA, NEBRASKA.

BLOCKING AND DERAILING DEVICE.

No. 873,377.

Specification of Letters Patent.

Patented Dec. 10, 1907

Application filed December 7, 1906. Serial No. 346,796.

To all whom it may concern:

Be it known that we, WILLIAM J. C. KENYON and WINFIELD S. KING, citizens of the United States, residing at Omaha, in the county of Douglas and State of Nebraska, have invented certain new and useful Improvements in Blocking and Derailing Devices, of which the following is a specification.

10 Our invention relates to new and useful improvements for blocking and derailing railway cars; and has for its object to provide an improved device of this kind by means of which a railway car coming in contact therewith will be derailed and thrown off the track.

To this end our invention consists in the combinations and details hereinafter described and claimed.

20 In the accompanying drawings—Figure 1 is a top plan view of our improved derailing device. Fig. 2 is a side elevation. Fig. 3 is a side elevation looking from the opposite side. Fig. 4 is a transverse sectional view on the line 4 of Fig. 1.

In carrying out our invention we provide an ear *c* which is secured to the web of the track by suitable fastening means, such as bolts *c*², and this ear is provided at its lower 30 portion with a hinge bolt *c*' upon which is mounted a derailing block *b*, this derailing block being provided with a web portion *b*¹ and spaced lugs *d*, the web portion *b*' being provided with hinge portions *b*' mounted 35 upon the hinge bolt *c*'. Between the spaced lugs *d* we mount an operating rod *e* by means of which the derailing block may be swung away from the track out of operative position or over the track into operative position.

40 One feature of our derailing block consists in the head thereof, which, as shown, is elongated and has at one end an inclined portion *b*² in line with the track. This inclined portion is of gradual ascent, in order that 45 the wheels of the car may ride up thereon without undue shock to the derailing block. This head is also provided with a derailing flange *b*³ which is integral with the head and extends from a point just in advance of the inclined portion *b*² across the track diagonally to the opposite end of the

derailing block. It will be observed that the inclined portion *b*² extends upwardly to a point *b*⁵ above the level of the head of the block, the purpose of this elevation being to 55 raise the wheels away from the track, so that the flange will not strike against the end *b*⁶ of the block between the derailing flange and the inclined portion.

In operation, the wheel striking the inclined portion *b*² will run thereupon, its flange being raised away from the end of the derailing block, so that it will strike against the side of the derailing flange and will be directed diagonally across the track. Thus, 60 the car will be thrown off the track, as will be readily understood. It will be observed that the opposite end *b*⁴ of the derailing block has an inclined portion in line with the track. This inclined portion is of gradual 65 ascent, in order that the wheels of the car may ride up thereon without undue shock to the derailing block, and it is provided with an ear for the purpose of guiding and engaging the wheel in its ascent upon the block. We 70 have found by experience that with this construction cars may be run over the block from this end without being thrown off the track. It will be understood that by means 75 of the operating rod *e* the derailing block 80 may be thrown into operative position over the track when it is desired to derail an approaching car. Under usual conditions, however, the block will be thrown away from the track out of operative position. 85

A car wheel passing from the right to the left of the device, as shown in Figs. 1 and 2, will first be elevated by reason of the tread part of the wheel riding up on the incline *b*³, then the flange of the wheel will encounter 90 the inclined flange *b*² of the derailing device and will thereby be derailed. Passing in the opposite direction, that is, from left to right, the tread of the wheel will rise upon the incline *b*⁴ and the flange of the wheel will contact with the surface of the ear *s* and will ride up the same and across the flange *b*³ and down over the opposite end of the device without being derailed. The weight of the wheel and the car is thus supported upon the 10 flange of the wheel while the latter is riding up the incline, the function of the ear *s* being

to carry the flange of the wheel over and across the flange b^3 .

We claim:

5 A derailing device, comprising an inclined part in line with the track, a flange inclined transversely to the track, said flange sloping downward to the track at the end opposite

said inclined part, and an inclined ear at the side of said flange.
